Application August 3, 1936, Serial No. 93,978

5 Claims. (Cl. 38—41)

The invention relates to new and useful improvements in power operated garment presses, and more particularly to such improvements in automatic valve mechanisms for controlling the 5 operation of such presses.

Objects and advantages of the invention will be set forth in part hereinafter and in part will be obvious herefrom, or may be learned by practice with the invention, the same being realized 10 and attained by means of the instrumentalities and combinations pointed out in the appended 15 claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of 20 the invention.

Of the drawings:

Fig. 1 is an elevation of a machine embodying the invention;

Fig. 2 is an enlarged detail, with parts in section and parts in plan, of the controlling valve mechanism, taken on the line 2—2 of Fig. 1;

Fig. 3 is a similar detail view, with parts in elevation and parts in section, taken on the line 3—3 of Fig. 2;

Figure 4 is a detail view of the same mechanism and the actuator therefor, this mechanism being shown in the assembly near the center of Fig. 1;

Fig. 5 is a diagrammatic view of the fluid pressure actuating mechanism and the controls therefor, and shows also diagrammatically tandem control for two presses;

Fig. 6 is a vertical section through a different form of valve mechanism taken on the line 6—6 40 of Fig. 7; and

Fig. 7 is a full elevation looking at Fig. 6 from the left.

An object of the invention is to provide an improved garment pressing mechanism which is 45 simple, powerful and accurate both in construction and operation, in which a garment pressing device is moved to and from the working position and a final pressing action of slight movement but great power is imparted to press the garments; to provide in such a mechanism a novel and very simple and reliable valve mechanism for controlling the fluid pressure to move the parts and to exert the final powerful garment pressing action; to provide simple but reliable automatically acting fluid pressure operated means

for applying the powerful pressing action, and for holding it at the option of the operative; to provide in such simplified mechanism against stalling and back action of the mechanism; to provide a controlling valve mechanism in which there is 5 maximum elimination of mechanical parts and at the same time great simplicity of the air pressure controlling means concomitant with increased smoothness and reliability of action.

Referring now to the embodiment of the invention illustrated by way of example in the accompanying drawings, it is shown applied to a garment pressing machine having a frame comprising a base 1 and vertical legs or members 2 supporting a horizontal table 3. Mounted upon 15 and projecting upwardly from the table 3 is a pillar or gooseneck 4 on top of which is mounted a lower or stationary pressing buck 5. The embodied means for supporting and actuating the upper or movable pressing buck 10 comprises a 20 lever 11, pivotally mounted at a median point 12 on a pillar 13 which is integral with and extends upwardly from the general frame of the machine. The upper buck 10 is mounted to have resilient and conforming pressure upon the garments being 25 pressed, and so far as concerns the present invention any suitable means for effecting this pressure may be employed. As shown, a knife edge pivotal mounting is furnished by a V-shaped recess 16 formed in the top of the buck into which 30 projects a narrower V-shaped knife edge projection 17 which is fixed on and projects from the outer part of the arm 11. The buck 10 is resiliently supported by a plurality of springs 18, 19 and 20, which press the members 16 and 17 35 yielding together, while permitting resilient rocking of the buck 10. Either or both of the bucks may be supplied with heating means, and as shown the upper buck 10 is so equipped, steam being supplied to the interior thereof by a pipe 21. 40

In the embodied form of actuating means for the lever 11 and the buck 10 (Fig. 1), they are held in the elevated or idle position by suitable resilient means, and from that position they are preliminarily swung downwardly into position 45 closely adjacent to the work, and then the work pressure is exerted on the garments by pneumatically operated mechanism, working against said resilient means. As embodied, the resilient moving means comprises twin tension springs 50 30 and 31, which are fixed at their lower end to a yoke 32, which is pivotally mounted at 33 on the machine frame. These springs at their upper ends are fastened to rods 36 and 37, fixed to and projecting from a yoke 38, which is pivoted 55

at 33 to the lever 11 near the opposite end thereof from the buck 10. These springs maintain the lever and buck resiliently in the elevated or idle position, and automatically return them to 5 that position after the pressing operation is completed.

In the power-operated means for doing the pressing, as embodied, a rod 47 is pivotally connected at its upper end 48 to the end of the arm 11, and its lower end rod 47 is pivotally connected at 50 to a lever 51. The embodied form of actuating means (Figs. 1 and 5) comprises a cylinder operating by air pressure and having two pistons therein connected by linkage to the 15 rod 47. The pistons are movable together from the top to the bottom of the cylinder to swing the arm 11 to the working position against the action of springs 30 and 31 and are movable in opposite directions, under interposed air pressure 20 to effect the short but heavy pressing movement. As embodied, a cylinder 54 is pivotally suspended at its top end by means of upwardly projecting arms 55 and 56, which are pivotally supported at 57 upon the machine frame. Within cylinder 25 54 is a lower piston 59, to which is fixed a piston rod 60, projecting through the bottom head of the cylinder and pivotally connected at 61 to the other end of the lever 51. Piston rod 60 is hollow to provide an air conduit into the space between 30 the pistons, as will be later described. Also within the cylinder 54 is an upper piston 63, to which is fixed a piston rod 64, which projects through the upper head of the cylinder. Piston rod 64 at 65 has a pin-and-slot connection with one end 35 of a lever 66, which is pivotally mounted at 67 upon the machine frame. Pivotally connected to the opposite end of the lever 66 at 68 is a rod 69. The other end of rod 69 is pivotally connected at 70 to a bent lever 71, which is pivotally supported at 72 upon the machine frame, the 40 other end of the lever being pivotally connected at a median point 73 to the lever 51.

The manner of operation of the precedingly described mechanism is substantially as follows: 45 When the press is idle and the buck 10 is in the elevated position, in which it is resiliently held by the springs 30 and 31, the pistons 59 and 63 are in the upper part of the cylinder 54, as shown at the right in Fig. 5. Air is first admitted into the top of the cylinder 54 above the 50 pistons, and they are driven downwardly together, this movement swinging lever 51 about its pivot 73 on lever 71, and with it the lower end of rod 47. The upper end of rod 47 concurrently rocks 55 about its upper pivot connection 48, and during this movement arm 11 swings counterclockwise about pivot 12, and at the end of this movement buck 10 is just above the work resting on buck 5, and rod 47 and lever 51 are in the straight-line relation shown in Fig. 1. During this joint movement of the two pistons, lever 66 also has been rocked clockwise about its pivot 67, and it in turn has rocked through a very small arc the 60 lever 71, this movement being substantially idle 65 so far as concerns the operation of the machine. When the mechanism is in this position, the buck 10 is just above the garments resting on the stationary buck 5 and is ready to receive the short movement and heavy pressure required to 70 press the garments. The air pressure is now relieved above the piston 63, and air pressure is introduced between the two pistons through the conduit in hollow piston rod 60. By this pressure piston 59 is held at the bottom of the cylinder 54, holding 75 pivot point 61 stationary, and piston 63 is

moved upwardly, thereby rocking lever 66 about its pivot 67 in counterclockwise direction. This produces powerful pressure on rod 69, which rocks lever 71 counter-clockwise, and this exerts a strong longitudinal, straight-line thrust on the made toggle 51, 47 and presses the buck 10 powerfully against the garments. The ratios of the lever arms are arranged to give a very powerful pressure on the work.

In the embodied form of operative actuated air pressure control, a double or two-handed valve mechanism is provided, requiring the use of both hands of the operative to actuate the machine, thereby insuring against injury to the operative's hands by the mechanism. This manually actuated valve control primarily brings the arm 11 and the buck 10 to the operative position just above the work, and thereupon air-pressure operated means are automatically called into operation to put on the powerful pressure for pressing the garments. Means are incorporated with the aforesaid mechanism for insuring certain and smooth institution and operation of the automatic mechanism, as will hereinafter be more fully described. As embodied, air pressure is supplied from any suitable source to a pressure header 81. A pipe 82 connects from the header 81 to the first of the two series connected manually operated valves, that is, a valve mechanism 83, which is spring-closed and manually opened. The valve has at one end an air chamber 84, into which the pipe 82 connects, the chamber being normally under the air pressure. The valve is double having valve disc 85 admitting pressure to the mechanism and valve 86 normally exhausting to the atmosphere. The valve discs are connected by a rod 87, one end of the rod projecting from the opposite end of the valve casing for manual operation. A spring 88 cooperates with the air pressure in the chamber 84 to hold the valve 85 normally closed against the air pressure from the header 81. The air chamber 84 communicates with the air passage 89 when valve 85 is opened by manual actuation by the operative, and by the same movement valve 86 cuts off the exhaust. 45 Each of the manual controls for opening the valves to let the air pressure into the machine comprises a lever 90, pivotally mounted at 91 on the valve casing, the tail end 92 of the lever contacting with the external end of the valve rod 87, 50 so that when the levers 90 and 90^a are pressed by the attendant the air will be passed through the valve to operate the machine. Air passage 89 in the first valve 83 connects by a pipe 94 with the air chamber 84^a of a second valve 96, which puts 55 valve 96 in series with the valve 83. The two valves are preferably identical in structure and the corresponding parts of valve 96 are indicated by the same reference numerals with exponents ^a added. When valves 83 and 96 are closed, the air passages 89 and 89^a communicate with the atmosphere through vents 93 and 93^a.

From the air passage 89^a the pipe 97 conveys the air pressure through flexible pipe 98 into the top end of the cylinder 54. Thus when the hand levers 90 and 90^a are simultaneously pressed by the operative, the air pressure from the header 81 is admitted above the pistons 63 and 59, moving them downwardly together and swinging the arm 11 and buck 10 up to the working position, as 70 previously described.

Referring now to the automatically operated air pressure means for exerting the further powerful pressing action on the garments (Figs. 2 to 5), a valve mechanism is provided for releasing the 75

air pressure previously exerted above the pistons, and for introducing air pressure between the pistons. As embodied, a valve 110 is mounted on a bracket 111 mounted on the machine frame. This valve comprises a chamber 112, into which the compressed air from the header 81 is normally admitted through a pipe 113. Within the chamber is a double valve, having a valve disc 114 within chamber 112 and normally closing a port 10 from chamber 112 into an air passage 115. Disc 114 is mounted on a rod 116, and on the other end of the rod is mounted a valve disc 117, this disc having an actuating rod or projection 118 extending through and projecting outside the valve casing. A spring 119 is in compression between the valve disc 114 and a screw-plug 120 which closes the end of the valve. Both the air pressure from pipe 113 and the spring 119 normally hold the valve disc 114 in closed position. A pipe 121 20 communicates from air passage 115, by means of a flexible pipe 128, to the air passage within the hollow piston rod 60 whereby the air pressure is introduced between the pistons 59 and 63 when valve 114 is automatically opened by the mechanism just at the end of the movement of the buck 10 up to the work ready to exert the heavy pressure thereon.

The means for actuating valve mechanism 110 to automatically exert the heavy pressure on the garments is operated by the movement and position of the mechanism which swings arm 11 to bring the buck 10 into position just over the work lying on the buck 5, as just described. Means are likewise provided for insuring certainty in the 35 operation of the valve mechanism 110, and also devices for holding the pressure on the work until released by the operative. As embodied (Fig. 1), an arm 135 is fixed to, and extends downwardly from, the lever 66, and the actuating device which 40 engages valve 110 is mounted in the end of the lever 135, the parts being proportioned and positioned so that the valve will be actuated automatically immediately on the two pistons reaching the bottom of the combined down stroke, at 45 which time the lever arm 135 is at the extreme left end of its travel in Fig. 1. The arm 135 swings backwardly toward the right during the independent upward movement of the piston 63. The embodied form of valve actuating means 50 comprises a head 136, integral on the end of the lever arm 135 (Figs. 1 and 4). Within the hollow head 136 is mounted a longitudinally reciprocal pin 137. This pin is urged outwardly, to the left in Fig. 4, by a compression spring 138 coiled about 55 the reduced shank 140 of the pin 137 and in compression between the rear of the pin head and the back end of the recess 141 within the head 136. The forward movement of pin 137 is limited by a lock nut 142 screw-threaded on the 60 rear end of the shank 140, which projects rearwardly from the back of the head 136. The spring 138 is more powerful than the spring 119 plus the force of the air pressure on disc 114 (Fig. 2) so as to provide sufficient yielding pressure to readily 65 and quickly open the valve at 114 and close it at 117.

The holding means for effecting delayed or continued pressure on the work, as embodied, operates by the air pressure. As so embodied (Figs. 2, 3, and 4), a bent lever 148 is pivoted at 149 on a bracket 150, which is fixed to and projects from the valve casing. The head 151 of the lever arm rests against the projecting end 118 of the valve stem. In the opposite end of bent lever 75 148 is mounted a screw-threaded pin 154, the

inner end of which abuts against the outer end of a pin 155 mounted to move longitudinally in a boss 156 in the casing 157 of the auxiliary holding valve. The inner rounded head of pin 155 abuts against a diaphragm 158, mounted within 5 the chamber 159 to form an air-tight partition. A port 160 communicates between the valve chamber 159 and the air passage 115 previously described. To further insure certainty and smoothness of action, and to guard against possible play or variation in the movement of the parts, as embodied, an air-actuated interponent mechanism is provided whereby a movable member is interposed between the head 151 of the bent lever 148 and the actuating pin 137 of the 10 lever arm 135. In said mechanism, as embodied, a valve casing 164 is mounted upon or integral with the structure of the valve 110. Within the chamber 165 of this valve is a diaphragm 166, forming an air-tight partition within the chamber. Reciprocably mounted in the valve casing is a pin 167, having a rounded head 168 resting against the diaphragm 166, the shank of the pin extending outside the valve casing. A coiled spring 169 is in compression between the back 20 of the head of the pin and the valve casing to hold the pin lightly to the diaphragm. Pivotaly mounted at 171 to the outer end of pin 167, exteriorly of the valve casing is a block-like interponent 172, this interponent being movably 25 mounted within and supported by a rectangular, apertured frame 173, mounted on and projecting from the valve casing. The rear part of chamber 165 behind the diaphragm 166, communicates by a pipe 174 with the air pressure 30 pipe 97 previously described herein.

The manner of operation of the precedingly described actuating and holding mechanism is substantially as follows:

To direct the air pressure between the pistons 40 to automatically impart the heavy pressure to the work: This is done by actuating double valve 114, 117. When the valve handles 90 and 98^a are manually actuated, the air passing through pipes 97 and 98, drives both pistons 59 and 63 down- 45 wardly together, thereby swinging arm 11 in the counter-clockwise direction and bringing the buck 10 just above the work, and during this movement lever 66 and arm 135 swing in clockwise direction. During this movement of the pistons, 50 the air pressure also passes from pipe 97 through pipe 174, and the resultant pressure in valve chamber 165 moves interponent 172 outwardly into alignment with the head 151 of lever 148, that is, from the position of Fig. 3 to that of 55 Fig. 4. Just as lever 135 reaches the end of its clockwise movement just described, pin 137 engages the back of the pivoted interponent 172, and with strong yielding pressure moves the double valve 114, 117 to the left in Fig. 2. This 60 opens the port at 114, letting the air pressure into pipe 127, and closes the port at 117, shutting off the exhaust. Thus the air pressure from pipe 113 passes through chamber 115, pipe 127, and hollow piston rod 60 to move piston 62 upwardly, while piston 59 is held at the bottom of the cylinder, as already described.

To automatically hold the heavy pressure on the work until manually released by the operator: Immediately on the opening of valve 114, as 70 previously described, the permanent maintained air pressure from the header 81 passes through the port 160 into air chamber 159, whereupon diaphragm 158 projects pin 155, and arm 148 holds the double valve 114, 117 in the open posi- 75

- tion until the air pressure in chamber 159 is manually released by the operative as later described. This manual release of the air pressure from the holding mechanism comprises a valve 5 chamber 181, communicating by a pipe 182 with a port on the pressure side of the air chamber 159. Valve chamber 181 is provided with a disc 183 normally pressed by spring 184 to close a port 185 which communicates with the atmosphere.
- 10 The stem 186 of the valve 183 projects from the casing, and a pivoted handle 187 is mounted on the casing, and when swung by the operator opens the valve 183 and relieves the air pressure from the chamber 159. Thereupon spring 119 closes valve 114 and opens valve 111, and connects pipe 127 with exhaust pipe 191, thereby relieving the pressure between the cylinders, and permitting the springs 30 and 31 to swing the arm 11 clockwise back to the open or idle position.
- 15 In Figs. 6 and 7 a different form of valve mechanism for exerting and controlling the final pressing movement is shown. The structural features of this valve are very simple, comprising only a few substantially rectangular plates and blocks 25 which may be readily cored or machined from the exterior and which require relatively little work of either kind. The valve has no external movable parts, and is assembled by bolting the plates and block together, as by screw-bolts 199.
- 20 In the body or block 200 is formed an air chamber 201, which communicates by a pipe 202 with the operative-controlled air valves 90 and 90^a, as by the pipe 202, which is the same as the pipe 174. Air chamber 201 communicates by an air passage 203 with an air chamber 204, having an exhaust port 239. A double valve has a disc 207, controlling the port between chamber 201 and air passage 203, and a valve disc 209, controlling the port between air passage 203 and an air 25 chamber 204, the two valve discs being carried on a rod 208 to move together. A coiled spring 210 acts to normally hold valve 207 closed and valve 209 open. This double valve has an actuating pin 213 projecting from the rear of valve disc 209, and projecting through the wall of the 30 valve casing, and this projecting end is engaged by the pin 137 to operate the valve.
- 35 Another air chamber 219 is formed in the rear part of the valve block and communicates by an air passage 220 with an air chamber 221. A double valve has a valve disc 222 which controls the port between the chamber 219 and passage 220, and a valve disc 224 which controls the port between the passage 220 and an air chamber 221, the discs being connected by a rod 223. A coiled 40 spring 225 normally holds valve 222 closed and valve 224 open. A diaphragm 231 constitutes the outer wall of the air chamber 221, and on the outside of this diaphragm is an air chamber 232, the other wall of which is a diaphragm 233, and 45 outside the diaphragm 233 and between it and the outer casing of the valve structure is an air chamber 234. A spacing device 235 is interposed between the diaphragms 231 and 233 to maintain them in spaced-apart relation and to communicate pressure and movement from one to the other.
- 50 Air chamber 204 has an exhaust port 239, and an air passage 240 communicates between air passage 203 and air chamber 232. An air pipe 70 communicates between the pressure header 81 and air chamber 219, and corresponds to air pipe 113 previously described and bears the same numeral. An air pipe communicates between air passage 220 and the hollow piston rod 60, and has 75 the same function as pipe 127 previously described

and bears the same number. An air passage 243 communicates between air passage 220 and chamber 234. An exhaust port from air chamber 234 connects into pipe 191. The valve rod 223 at its right-hand end has a rounded projection, 5 making a socket fit within a hollow plate 245, mounted on the diaphragm 231, whereby pressure against the diaphragm will open valve 220 and close valve 224 against spring 225.

The operation of the mechanism just described 10 is substantially as follows:

When the air pressure is admitted by the manually operated valves 90 and 90^a, air chamber 201 is put under pressure at the same time that the air pressure through pipe 98 drives both pistons 15 downwardly together to swing arm 11 to bring the pressing buck 10 to the work. At the end of this movement, pin 137 engages head 213, pushes it inwardly, and thereby closes valve 209 and opens valve 207. The air pressure, passing 20 through passage 203 and port 240, enters chamber 232, and by moving diaphragm 231 to the left closes valve 224 and opens valve 222. This admits the air pressure from the header 81 through pipe 113 into passage 220, and also 25 through passage 243 into air chamber 234, and diaphragm 233 is therefore moved to the left and placed under pressure to hold valve 222 open. Pin 137 in the meantime has receded from the head 213, and valve 207 has closed and valve 209 30 has opened, and air chamber 233 is exhausted to the atmosphere through port 239. The pressure in chamber 234 will be maintained and will hold valve 222 open and valve 224 closed until the pressure in pipe 127 and chamber 134 is released by the operative tripping the valve 183. That is, the heavy pressure will be maintained on the work until the operative trips valve 183.

Means are provided in accordance with one feature of the invention for operating two pressing machines in tandem, and such an arrangement is shown diagrammatically in Fig. 5. When the machines are operated separately, the valves 251 and 252 are closed, and where one machine is operating independently there will be no pipe 40 connections between the two machines. The automatic control for the two machines, as embodied, comprises a valve 254, which communicates by a pipe 259 with the air pressure pipe 97 which is controlled by the manually-operated 50 valves 90 and 90^a. The valve 254 has a diaphragm 262, the air pressure from pipe 259 acting on the diaphragm within a chamber 263. In contact with the opposite side of diaphragm 262 is the stem 264 of a valve 265, which valve controls an 55 exhaust port opening from the air chamber 266. A spring 267 normally holds the valve 265 closed, except when pressure is admitted to chamber 263 to open the exhaust valve against the pressure of the spring 267. Chamber 266 communicates by a 60 pipe 268 with the pipe 182 (previously described) which is in the exhaust line between the pressure chamber 159 of the valve mechanism shown in Figs. 2 and 3, and the operative-actuated release valve 183. When the machines are operated in tandem, and the valve handles 90 and 90^a are actuated to open the valves to put the pressure for the initial stroke on the left-hand press, the air pressure through pipe 259 will open the exhaust valve 265 and take the holding pressure off the other press; and in like manner when the valve handles 90^c and 90^d are operated to put the heavy pressure on the right-hand press, the holding pressure will be relieved on the other press.

The invention in its broader aspects is not 75

limited to the specific mechanisms shown and described, but departures may be made therefrom within the scope of the accompanying claims without departing from the principles of 5 the invention and without sacrificing its chief advantages.

What I claim is:

1. In a garment pressing mechanism having a pair of cooperating pressing bucks, at least one 10 of said pressing bucks being movable to and fro between the work pressing position and an idle position, a mechanism including a plurality of levers, a cylinder having two independently movable pistons, means for moving the pistons together and separately and separate connections 15 from the pistons to said levers for moving a pressing buck to and from the work pressing position and for exerting heavy pressure on the work, valve mechanism for supplying fluid pressure to 20 said mechanism to move said pressing buck to the work pressing position, valve mechanism operating automatically to apply fluid pressure to said mechanism to press the buck heavily against the work, means supplied with fluid pressure by 25 the opening of said last-mentioned valve mechanism and operating automatically to maintain fluid pressure to hold the heavy pressure against the work, manually operated valve mechanism for releasing the pressure on the work, and means 30 for moving said pressing buck away from the work pressing position to the idle position.

2. In a garment pressing mechanism, a pair of bucks, means including a multiple piston cylinder for bringing one of the bucks to the work, an air 35 supply therefor including an automatically closable valve and workman-operated means for opening the valve, and means including an air supply to effect heavy pressure upon the work and a valve therefore operated by the mechanism, and 40 fluid pressure means operating to hold said valve open to continue the heavy pressure on the work.

3. In a garment pressing mechanism, in combination a pair of pressing elements, one of 45 said elements being movable, means for moving one of said pressing elements, including a cylinder having two pistons and connections therefrom to said pressing element, the connections from one piston moving said pressing element to and from the work, the connections from said 50 other piston acting through said first-mentioned

connections to press said pressing element heavily on the work, said connections comprising a medianly pivoted lever connected at one end to a piston rod and devices connected to the other end of said lever for effecting said heavy pressure. 5

4. In a system of garment presses comprising first and second presses, the combination of control means for operating said presses by fluid pressure comprising separate fluid-pressure 10 means for the first and second presses to impart closing and heavy ironing pressure movements separately to the respective presses, separate operative-actuated means including control valves to control the admission of fluid pressure separately to said fluid-pressure means for each press, separate means on the first and on the second presses respectively for holding the heavy ironing pressure thereon, said holding means being operated automatically by valves actuated by the 15 movement of its respective press, each press having a separate fluid-pressure release valve for releasing said holding pressure, and a connection between the fluid-pressure control valve for the first press and the release valve for the second 20 press to automatically operate said release valve to open the press by the turning on of the fluid pressure for closing the first press, and a connection between the fluid pressure control valve for the second press and the release valve for the 25 first press to automatically operate the release valve for the first press to open the press by the turning on of the fluid pressure for closing the second press, whereby one press is released of 30 ironing pressure as closing pressure is applied to 35 the other press.

5. In a garment pressing mechanism having stationary and movable pressing elements, a fluid actuated member for forcing said movable pressing element heavily against the work on said stationary element, a valve for admitting fluid pressure to actuate said member, a second valve, means comprising a pressure operated pivoted arm adapted to be operated automatically by the admission of fluid pressure through said valve to 40 open said second valve to maintain fluid pressure upon said actuating member and thereby to 45 maintain the heavy pressure upon the work.
